UNITED STATES PATENT OFFICE.

ALBERT B. DISS, OF NEWARK, NEW JERSEY, ASSIGNOR TO UNIVERSAL CASTER & FOUNDRY COMPANY, OF NEW YORK, N. Y., A CORPORATION OF NEW JERSEY.

SLIDING SHOE FOR FURNITURE-LEGS AND OTHER USES.

1,228,759.

Specification of Letters Patent.

Patented June 5, 1917.

Application filed April 14, 1914. Serial No. 831,723.

To all whom it may concern:

Be it known that I, ALBERT B. DISS, a resident of Newark, in the State of New Jersey, manufacturer, have invented certain new and useful Improvements in Sliding Shoes for Furniture-Legs and other Uses, of which the following is a specification, accompanied by drawings.

It is frequently desired to mount bedsteads and other furniture on slides or sliding shoes instead of wheel casters. Sliding shoes of glass are, for many conditions, preferable to metallic shoes, because of smoothness, resistance to corrosion, cleanly appearance or other advantages, including indeed, in the fancy of some users, the fact that a glass or non-conducting shoe is thought to afford some protection to a metallic bedstead against lightning. In such shoes, it is usually desired or required that the shoe shall be free to turn upon a vertical pin or axis, so as to lessen friction, particularly in passing over uneven floor surfaces.

The present invention provides an improved construction of sliding shoe suitable particularly for legs of bedsteads and other furniture, which is simple, efficient, durable and reliable in use, and which does not readily break nor get out of order, and is comparatively inexpensive to manufacture and is easily attached to and removed from the leg.

The invention will be readily understood from the following description and claims.

35 In the drawings,

Figure 1 is a side view, partly in section, and partly broken away to show details, of the preferred embodiment of the invention as applied to a tubular leg;

40 Fig. 2 is a top view of the same, showing the leg in section;

Fig. 3 shows another form of the invention, without certain features of the construction shown in Fig. 1.

45 Referring first to Figs. 1 and 2, at 10 is shown a portion of a tubular leg or bedpost. At 11 is shown the shoe proper, preferably of colorless transparent glass, though in designating glass I do not wish to exclude the 50 substitution of other suitable compositions. The shoe 11 should have a very slightly cambered or convex lower face, being flat or substantially flat at a comparatively small central area and rounded at the periphery, as 55 illustrated. The upper face of the shoe 11

is provided with an annular overhanging shoulder or head 12, by which it is attached, and a central recess 13, affording a space for the riveted lower end of a pintle. Attaching plate 15 fits upon the top of the shoe, 60 and is provided with teeth 16 around its edge, which are turned downward and inward upon and beneath the overhanging shoulder 12, so as to rigidly secure the attaching plate to the shoe by means of its 65 inturned teeth. The pintle 20 is rigidly joined to the attaching plate 15 by extending through a perforation in the center of the plate and having an enlargement above the plate and a riveted head 21 beneath the 70 plate, as shown. The upper end of the pintle is provided with projections 22, forming an enlargement or head for securing the pintle to the spring frame or socket. The leg supporting plate 25 surrounds the pintle 75 and carries the weight of the leg 10. This leg supporting plate preferably serves to relatively center the leg and the lower end of the pintle, but the spring frame may serve this purpose alone or jointly with the 80 leg supporting plate. For so centering the leg, the leg supporting plate is provided with an annular shoulder 26, internally fitting the lower end of the leg. The leg supporting plate is provided with a downturned 85 member, which is here shown as an integral part of it and which extends outward from beneath the foot of the leg and is curved downward and then inward in a graceful curve extending around and thus substantially housing the shoulder 12 of the shoe 90 and the attaching teeth 16.

Between the leg supporting plate and the attaching plate are interposed ball bearings 31, which may, as shown, be provided with 95 an upper annular ball cup or ball race 30, separate from the leg supporting plate 25, and loosely secured around the pintle by upsetting the metal of the pintle to form a projecting flange above the inner edge of 100 the ball race. To accommodate ball bearings and at the same time strengthen the leg supporting plate, the plate is preferably domed at its center, as shown. The weight of the leg and leg supporting plate bears on 105 the ball bearings, the balls 31 of which in turn bear directly upon the attaching plate 15 or on the collar on the pintle or both.

Above the leg supporting plate there is secured to the pintle a spring frame 32, which 110

fits around the pintle beneath, and is secured by, the projections or head 22, and approximately fits and centers the pintle at its upper end and the interior of the tubular leg. The expandable side members of the frame act frictionally on the interior of the tubular leg to hold the frame, and consequently the pintle, in the leg and thereby secure the slide to the leg. The lower end of 10 the frame may also approximately fit and center the pintle and the leg, although it will be seen that this function may be left solely to the leg supporting plate, as described. The form of spring frame shown 15 and described is the one I prefer on account of its simplicity and because it has been thoroughly tested by years of service in casters for tubular legs.

In the form of the invention shown in 20 Fig. 3, some of the features of the invention as above described are omitted, and the slide operates without ball bearings. The pintle 201 has a shoulder 202, on which the leg supporting plate 250 directly rests. The 25 leg supporting plate is shown with a shoulder 260 for centering the leg and with an ornamental upturned periphery forming a leg mount 251, which, if present, can be made to fit the exterior of the leg and also 30 serve the function of centering the leg externally; and the attaching plate 15 and shoe 11 are the same as in Fig. 1, the pintle being riveted to the plate in the same manner.

The operation of the sliding shoe will now 35 be evident without further explanation. It will be seen that the manner of attaching the glass or other shoe to the pintle is a very secure one and, at the same time, it is designed to avoid danger of chipping or breaking 40 the glass, or other brittle substance of which the shoe may be composed, under shocks and strains that inevitably occur in sliding furniture over uneven floor surfaces.

This shoe provides a broad, nearly flat 45 surface, suitable for acting on carpets or rugs without injury thereto. The shoe is free to turn with its pintle when subjected

to greater sliding friction on one side than the other, thereby both lessening the frictional resistance and relieving the device of 50 twisting strains.

Although I have shown the invention in a form suitable for use with tubular legs, it will be understood that the shoe, pintle and attaching plate are applicable also to wooden 55 legs and to various caster sockets for the pintles of detachable casters.

I claim the following:

1. The combination of a sliding shoe having a central recess therein, an attaching plate fitted and secured to the shoe, a pintle rigidly joined to the said attaching plate, said pintle having an enlargement above the plate and a riveted head beneath the same in said recess, a leg-supporting plate 65 surrounding the pintle, means for securing the pintle within the leg and permitting its rotation during conditions of use, and ball bearings between the leg-supporting plate and the attaching plate, the leg-supporting 70 plate being domed at its central portion to accommodate said ball bearings.

2. The combination of a sliding shoe having an overhanging curved shoulder and a central recess, and an attaching plate therefor provided with a pintle extending through the plate and riveted fixedly thereto with its lower end enlarged and received within the said recess in the shoe, said attaching plate having a series of teeth 80 engaging with and beneath said overhanging shoulder, and a leg supporting plate having a downturned edge portion extending around the said attaching plate and means for frictionally attaching all the said parts 85 to a leg.

In testimony whereof I have signed this specification in the presence of two subscribing witnesses this 10th day of April, 1914.

ALBERT B. DISS.
